OSCAR ZERK, NOW BY JUDICIAL CHANGE OF NAME OSCAR ULYSSES ZERK, OF CLEVE-
LAND, OHIO, ASSIGNOR, BY MESNE ASSIGNMENTS, TO THE BASSICK MANUFACTUR-
ING COMPANY.

OILING NIPPLE.

Application filed March 14, 1921. Serial No. 452,132.

My invention relates to an oil or grease nipple for allowing the application of lubricant. One object of my invention is to provide a means for retaining a dust cap about an oil nipple or the like, in such a manner that its accidental displacement is prevented, even when the device is subjected to heavy jars and vibration, but so that it may be easily removed when lubricant is to be applied to the nipple.

Another object is to provide members of such form that they may be quickly and economically manufactured. Another object is to provide a means for preventing loss of the cap, even if the operator neglects to replace it upon the nipple. Other objects of the invention will be apparent in the course of the following description, and features of novelty will be pointed out in the claims.

Referring to the drawings in which a device embodying the principles of my invention is illustrated, Fig. 1 a longitudinal section through such a device; Fig. 2 is a longitudinal section of a slightly different form of device; Fig. 3 is a section taken on the line 3—3 of Fig. 2; Fig. 4 is a section taken on the line 4—4 of Fig. 2; Figs. 3 and 4 illustrate features common to the forms of the device as illustrated both in Fig. 1 and in Fig. 2. Fig. 5 is a view of a different form of dust cap which may be employed. Fig. 6 is a longitudinal section through a device embodying the features of my invention showing a slightly different method of attaching the chain to the nipple.

Referring to the parts in detail, the devices illustrated include respectively nipples 10 and 10', which are similar in form, each having an enlarged end forming a cup 11. Within each of the nipple members there is a check valve, two slightly different forms being illustrated as will be described subsequently.

Each of the cup members has a circumferentially extending groove 12. In this groove the straight end of the spring 20 is adapted to extend. This will be clearly seen by reference to Fig. 4. This spring is arcuate for the greater part of its extent.

In order to protect the oil nipple a dust cap 25 is provided which is adapted to enclose the cup and has formed on its inner face a circumferentially extending groove

26. The arcuate portion of the spring 20 is seated in the groove with a chordal or extending portion protruding inwardly a sufficient distance from the wall of the cap member to engage the nipple and finally seat in the groove formed in the nipple wall when the cap is pushed down into locking position, as shown in Figs. 1, 2 and 6. It will be noted from Fig. 4 that when the cap is being moved, the chordal or straight portion of the spring member will be deflected outwardly slightly beyond the restrained position shown in Fig. 4 as the spring member is carried upwardly by the cap member.

An ear 27 may be stamped out of the material of the cup adjacent its open end to form an eyelet, while surrounding the nipple and abutting the shoulder thereon, is a member 28 having an opening in its central portion through which the nipple passes and having one end bent up and an opening stamped therein to form another eyelet. The cap member may be made of such a length as to have its end seat upon this member 28 when the cap is in the spring held position illustrated in Figs. 1 and 2. A chain 29 may be connected to the two eyelets to prevent the accidental loss of the cap when it has been removed from the nipple.

In Fig. 5, I have illustrated a form of dust cap, which is in some ways preferable to that shown in the other views, and may be substituted therefor. In this dust cap instead of stamping up a chain retaining member, from the metal of the cap, I weld or otherwise attach a strip of metal upon the wall of the cap 40. A short length of wire bent into U-shape may be employed and the most convenient manner of attaching this piece to the cap, I find to be electric welding. This method of construction is very simple, and has the further advantage in not leaving any opening for dust to pass into the interior of the cap.

In Fig. 6 I have illustrated a nipple 100 which is similar to that shown in Fig. 2 except that the chain attaching member of the nipple consists of the strip of metal or loop of wire 42, suitably secured as by welding, to the nipple 43. I also prefer to provide an annular member 44 suitably attached to the nipple and serving as a seat for the dust cap 25.

It will be seen from the foregoing description that the construction shown in Figs. 3 and 4 applies equally to Figs. 1, 2 and 6.

In the device illustrated in Fig. 1, the cup member 11 has retained therein a threaded sleeve 30. In assembling, the sleeve 30 should be inserted before the ends 13 are turned down. After this member is inserted the ends are turned or beaded down over the sleeve 30, thereby holding it tightly in place. The ball valve 31 and its retaining spring 32 are then inserted within the chamber and the threaded valve seat 34 is then screwed into the sleeve 30. The member 34 has a suitable opening to allow the passage of lubricant and may be provided with suitable sockets 35 to adapt it for the reception of a suitable manipulating tool which makes possible its ready removal and replacement. In this form of device the spring 32 is shown as seated on a shoulder at the far end of the nipple.

The device illustrated in Fig. 2 differs from that in Fig. 1 in the form of the valve illustrated. In this device the valve 36 and the spring 37 are preferably inserted before the end 13 of the cup is turned down. The spring 37 is seated at one end upon a shoulder in the cup and at its other end upon the valve member 36, and therefore acts to hold the valve 36 normally closed.

It will therefore be seen that I have provided a lubricant nipple which is adapted to hold a dust cap in position even when the device is subjected to heavy jars and vibrations, as is the case for instance where a nipple is carried on an automobile. At the same time by the arrangement which I have devised the cap may be very easily and quickly removed from the nipple when desired. It will also be seen that I have provided a simple means whereby the loss of the cap is prevented even though the operator should neglect to replace it after applying lubricant to the nipple.

While I have described a specific embodiment of my invention, it will be apparent that many changes might be made therein, and various devices might be made embodying the principles thereof. The foregoing illustration is therefore to be taken as illustrative of the invention rather than restrictive of its character and scope.

Having thus described my invention, I claim:

1. In a device of the character described, a lubricant receiving nipple having a groove in the outer wall thereof, a removable dust cap for enclosing the receiving end of the nipple and having an annular groove formed in the inner wall thereof, a spring member mounted in the groove of the dust cap and having a chordal portion adapted to engage the groove of the nipple.

2. In a lubricating device, a lubricant re-

ceiving nipple having an inlet formed therein, a dust cap covering the major portion of the nipple, said dust cap and the nipple having grooves formed therein which are oppositely positioned when the dust cap is on the nipple, an annular spring member carried in the groove of the dust cap and having a portion extending from the dust cap and adapted to engage in the groove of the nipple.

3. In a device of the class described, a cup member having a lubricant receiving opening, a dust cap adapted to surround said cup, a spring having an arcuate form throughout the greater part of its length and a straight end, a groove on said cup member adapted to receive said end, and a circumferential groove in the dust cap in which said spring is adapted to seat.

4. In a device of the class described, a pressed metal nipple having an enlarged cylindrical portion with a groove formed in the exterior surface thereof, a removable dust cap having a cylindrical portion with a groove formed interiorly thereon, an expandable member carried by the dust cap and positioned within the groove of the dust cap, said expandable member having an inwardly extending portion in the nature of a chord of a circle adapted to engage in the groove of the nipple.

5. In a device of the class described, a cup member having a threaded nipple in one end and an enlarged valve receiving chamber at its other end, a circumferential groove on said cup, a removable cap surrounding said cup having a groove therein, and an expanding spring carried by the cap groove and adapted to engage the groove in the nipple.

6. In a device of the class described, a cup member having a lubricant receiving opening therein, a disc member surrounding a portion of said cup member and abutting a shoulder thereon, an eyelet in said member, and a dust cap adapted to surround the cup member, and having an eyelet thereon, and a chain for connecting said eyelets.

7. In a device of the class described, a cup member having a lubricant receiving opening therein, a disc member adapted to surround a portion of said cup member and abutting a shoulder thereon, a dust cap adapted to cover the opening in said member and seat on said surrounding member, an eyelet stamped up from the cap, an eyelet formed on said surrounding member, and means for connecting said eyelets.

8. In a device of the class described, a cup member having a threaded portion at one end and an enlarged valve chamber at its other end, a circumferential groove on the exterior of said cup member, a second member surrounding said cup member adjacent the threaded portion thereof, an eyelet in

said second member, a dust cap adapted to surround said cup member and seat on said second member, an expanding spring carried by said dust cap, a groove in said cup member, adapted to receive said spring, an eyelet formed by stamping up a portion of said cap, and means for connecting said eyelets.

9. In a device of the class described, a lubricant receiving nipple having a contracted threaded portion at one end and an enlarged valve chamber at its other end, said enlarged portion having an annular groove formed exteriorly thereof, a slip-on dust cap having an annular groove formed interiorly thereof, a washer member mount-

ed on the contracted threaded portion of the nipple, an expansible spring member mounted in the groove of the dust cap and having an inwardly extending portion for 20 engaging the groove formed in the enlarged portion of the nipple, the respective grooves being formed in the dust cap and the nipple in such a manner that the spring member may maintain the dust cap with the lower 25 perimeter thereof substantially in contact with said washer member.

In testimony whereof, I hereunto affix my signature.

OSCAR ZERK,

*Now by Judicial Change of Name Oscar
Ulysses Zerk.*
